UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,229,183.

Specification of Letters Patent.

Patented June 5, 1917.

Original application filed May 14, 1913, Serial No. 767,499. Divided and this application filed February 21, 1916. Serial No. 79,550.

To all whom it may concern:

Be it known that I, LYMAN R. ROBERTS, a citizen of the United States, residing in Rutherford, in the county of Rutherford 5 and State of New Jersey, have invented certain new and useful Improvements in Type-Writing Machines, of which the following is a specification.

My invention relates to typewriting machines, and is herein disclosed as applied to a modified Underwood typewriting machine, wherein the usual type-bars strike against the front side of a traveling platen.

This application is a division of my application No. 767,499, filed May 14, 1913, (patented March 28, 1916, No. 1,177,140), and the present application is directed to a platen especially adapted to hold work-sheets of different characters, and large in 20 size, such as ledger sheets, statement sheets, proof sheets, etc. The platen is herein disclosed as a section of a cylinder, and is provided along its opposite edges with independently operable clamps or holders for 25 the work-sheets. These clamps project through openings in the platen, and serve as means to aline the edge of the work-sheet.

Other features and advantages will hereinafter appear.

30 In the accompanying drawings,

Figure 1 is an end elevation view of a typewriting machine, constructed in accordance with the principles of my invention.

Fig. 2 is a detail showing the line-space 35 mechanism.

Fig. 3 is a part sectional front view of the machine.

The platen 1 is rotatably mounted in a traveling platen frame or carriage 2, driven 40 by a spring motor 3, connected through a band 4 to the carriage. Bearing lugs 5 on the platen frame are slideable on a stationary carriage rail 6, on the machine frame 7. The front of the platen frame has a bearing roller 8 which runs on a stationary guide rail 9. The platen axle 10 is seated in bearings 11, and leaf springs 13 bearing on the upper surface of the platen axle serve to prevent accidental displacement of the 45 platen.

The platen may be rotated by means of hand wheels 14, on the ends of the platen, or any suitable form of line-space mechanism. As shown herein, the line-space mech-

anism comprises a lever 15 pivoted at 16 to 55 the platen frame, and having at its rear end a pivoted spring-pressed pawl 17, coöperating with a rack 18 on the left-hand end of the platen, the pawl 17 having a finger piece 17^a, for lifting the pawl from the 60 rack. The lever 15 is normally held in the position shown in Fig. 1, by a spring 19. When the free end of the lever is depressed, it is carried to the position shown in Fig. 2, the platen being rotated with it a distance of one line-space. As the lever 15 returns, the pawl rides idly over the rack and engages the next lower tooth of the rack. The platen is held against accidental rotation by means of a spring detent 20 having 70 a curved end 21, which seats between adjacent rack teeth, as shown in Fig. 3. The platen is preferably in the form of a section of a cylinder, and as herein shown is substantially semi-cylindrical. 75

It will be understood that the platen surface may extend through a greater or less arc, and, in some instances, may form a complete cylinder. The platen is of large diameter, as here shown, being in the neighborhood of 10 inches in diameter, so that the printing area is sufficient to accommodate any ordinary work-piece it is desired to place thereon. The radius of curvature being large, it is not necessary to bend or 80 curve the work-sheet sufficiently to prevent it from readily conforming to the platen surface, and this form of platen surface also facilitates the positioning and clamping of the work-sheet. 90

The means for holding a work-sheet in position comprises clamps 22, extending through the platen and having offset ends 23, which overhand the work-sheets, and clamp them against the surface of the platen. 95 The clamps are held in clamping position by springs 24. Each set of clamps is arranged in an arc of a circle, there being one set of clamps adjacent each end of the platen. Each set of clamps is released by 100 means of an arc-shaped bar 25 having cam surfaces 26 to engage the clamps and lift them to releasing position. The cam bar 25 is mounted on the inner side of the platen by means of brackets 27, secured to or 105 formed integral with the bar, said brackets slidably held against the inner face of the platen by shouldered screws 28 extending

through slots in the brackets and threaded into the platen. An arm 29 on the cam bar projects through a slot 30 in the platen, and has a knob or handle 31 for operating the bar.

In the position seen in Fig. 3, the clamps 22 are holding a work-sheet against the platen. Said clamps, however, are released by pulling the handle 31 downward, thereby causing the cams 26 to ride under the clamps 22, and cam the offset ends 23 clear of the platen. When thus clear of the platen, the work-sheet may be placed on the platen and the clamps serve to align the edge 15 of the work-sheet. If desired, the work-sheet may include notches adapted to register with the stems of the clamps.

The printing on a work-sheet is effected by types 32, on type-bars 33 pivoted on the usual curved fulcrum rod 34 and actuated by finger-keys 35 on key-levers 36 connected through bell-crank levers 37 to their type-bars. The key levers 36 are pivoted at the rear end of the machine at 38, so that when 25 a finger key is depressed, the corresponding bell-crank 37 throws its connected type-bar up to printing position in front of the platen.

The letter-feeding movement of the carriage is controlled by an escapement mechanism comprising an escapement wheel 39 connected, as in the usual Underwood typewriting machine, to a pinion 40 in mesh with a rack 41 on the typewriter carriage. Escapement dogs 42 and 43 which rock on a fulcrum 44 are connected through a link 45 with an arm 46 on a rock shaft 47, to which are also secured rock arms 48 carrying a universal bar 49 actuated by heels 50 on the type-bars. The rack 41 is carried on arms 40 pivoted at 52 to the platen frame.

Attention is called to the main application No. 767,499 (Patent No. 1,177,140), and also to a divisional application No. 851,707 45 (Patent No. 1,177,275 of March 28, 1916); the present application, which is a separate division of 767,499, being directed to the platen structure.

Variations may be resorted to within the 50 scope of the invention, and portions of the improvements may be used without others.

Having thus described my invention, I claim:

1. In a typewriting machine, the combination of a segmental platen mounted for ro-

tation about a horizontal axis to bring the printing surface thereon above the axis to face upwardly for the assembling thereon of work-pieces, said surface being of such large curvature and area as to form a sheet-collating board or table permitting, while in said position, the assembling thereon of a main ledger or analogous sheet and other sheets or forms overlying one another in different positions on the table, printing mechanism, and line-space mechanism to rotate the platen step by step for bringing the work-sheets thereon line by line into printing position, and a carriage on which the platen is mounted for letter-feed travel 60 in the direction of its axis.

2. In combination, a sheet-collating board curved to form a segment of sufficiently large diameter to permit the collation of sheets on all portions thereof simultaneously, the surface of said board being constructed to receive type-impressions, a set of types mounted to write upon the front of said collating board, and a letter-feeding carriage whereon said collating board is 75 mounted to rotate about its axis.

3. In combination, a sheet-collating board curved to form a segment of sufficiently large diameter to permit the collation of sheets on all portions thereof simultaneously, the surface of said board being constructed to receive type-impressions, a set of types mounted to write upon the front of said collating board, and a letter-feeding carriage whereon said collating board is 80 mounted to rotate about its axis, said segment being of substantially semi-cylindrical form.

4. In combination, a sheet-collating board curved to form a segment of sufficiently large diameter to permit the collation of sheets on all portions thereof simultaneously, the surface of said board being constructed to receive type-impressions, a set of types mounted to write upon the front of 95 said collating board, a letter-feeding carriage whereon said collating board is mounted to rotate about its axis, and means connected to said collating board for line-spacing the same.

LYMAN R. ROBERTS.
